UNITED STATES PATENT OFFICE

164,546

HOSE REEL OR THE LIKE

Nathaniel Becker, New York, N. Y., assignor to Wirt & Knox Mfg. Co., Philadelphia, Pa., a corporation of New Jersey

Application May 3, 1951, Serial No. 15,057

Term of patent 7 years

(Cl. D14—3)

To all whom it may concern:

Be it known that I, Nathaniel Becker, a citizen of the United States, residing in New York, county of New York, State of New York, have invented a new, original, and ornamental Design for a Hose Reel or the like, of which the following is a specification, reference being had to the accompanying drawing, forming part thereof.

In the drawing the figure represents a perspective view of a hose reel, showing my new design.

I claim:

The ornamental design for a hose reel or the like, as shown.

NATHANIEL BECKER.
